[57] ABSTRACT

A halogen-containing single-ended electric lamp of the type used in slide projectors is provided with a platinum-coated fuse wire of nickel or Nichrome alloy which is located within the envelope and connected in series with the tungsten filament. The platinum coating is of such thickness that it protects the wire from the hot corrosive atmosphere within the operating lamp and prevents the fusible core metal from contaminating the lamp and disrupting the halogen-regenerative cycle.

CROSS-REFERENCES TO RELATED APPLICATIONS

The present application is related to but constitutes an improvement over the subject matter disclosed and claimed in the following copending commonly-owned U.S. applications:

Application Ser. No. 100,665 filed Dec. 22, 1970 by N. J. Rainone et al. and entitled "Halogen-Cycle Incandescent Lamp Having An Improved Filament Mount Assembly;" and

Application Ser. No. 28,663 filed Apr. 15, 1970 by A. R. DeCaro et al. and entitled "Lamp Combination Comprising An Improved Envelope For Tungsten-Halogen Incandescible Projection Lamp," now U.S. Pat. No. 3,648,094.

BACKGROUND OF THE INVENTION

1. Field of the Invention

This invention relates to electric lamps and has particular reference to an improved halogen-cycle incandescent lamp of the type used in film projectors and similar apparatus.

2. Description of the Prior Art

Incandescent lamps having "built-in" fuse elements that are located within the lamp envelope are per se well known in the art. A conventional projection type lamp having such an integral fuse is disclosed in U.S. Pat. No. 2,859,381 issued Nov. 4, 1958 to S. M. Gray et al. Since such conventional projection lamps are filled with an inert gas such as nitrogen or the like, the fuse can be fabricated from any metal that meets the current-carrying requirements and has the proper rigidity and melting point to fulfill the automatic fusing function.

The situation in the case of the so-called "regenerative" type incandescent lamps is, however, quite different in that such lamps contain a highly-corrosive halogen atmosphere and operate at much higher temperatures in order to sustain the halogen-tungsten cycle which returns vaporized tungsten back to the filament. (This principle is well known and is described in detail in U.S. Pat. No. 2,883,571.) Tests conducted with fusible elements composed of bare copper, nickel, or Nichrome alloy wires have shown that they are not only chemically attacked by the bromine or other halogen gas used in the lamp but that the wires, when heated to the high temperatures which prevail within the operating lamp, released gaseous and other impurities which contaminated the lamp atmosphere. This, in turn, disrupted the halogen-tungsten cycle and formed discolored deposits on the lamp envelope which drastically reduced the light output.

A double-ended compact infrared heating lamp having a silica envelope and a seal structure wherein the portions of the lead-in conductors that extend from the press seals formed at the ends of the envelope and are exposed to the air are composed of platinum-sheathed tungsten or platinum-sheathed molybdenum is described in U.S. Pat. No. 3,012,167 issued Dec. 5, 1961 to F. E. Poole.

SUMMARY OF THE INVENTION

Briefly, the present invention provides a practical and inexpensive solution to the problem of fusing halogen-cycle type incandescent lamps by fabricating the internally-mounted fuse elements from either platinized nickel or a platinized Nichrome alloy. The layer of platinum is such that it protects the fuse from the hot halogen atmosphere within the lamp and prevents the nickel or Nichrome core portion of the fuse from releasing contaminants which disrupt the halogen-tungsten cycle. The improved lamp thus operates in the normal fashion and the fuse remains intact until such time that the filament fails and the resulting surge in current causes the fuse to melt and open the circuit.

BRIEF DESCRIPTION OF THE DRAWING

A better understanding of the invention will be obtained from the following description of the exemplary embodiment shown in the accompanying drawing, wherein:

FIG. 1 is a side elevational view of a halogen-cycle incandescent projection lamp having an internal fuse structure according to the invention; and

FIG. 2 is a cross-sectional view through the based end of the lamp, taken along line II-II of FIG. 1, showing the physical arrangement of the fuse assembly and the sealed-in pin members.

DESCRIPTION OF THE PREFERRED EMBODIMENT

In FIG. 1 there is shown a representative 500 watt halogen-cycle type projection lamp 10 having a light-transmitting tubular envelope 12 that is sealed by an end wall formed by fusing a disk or wafer 14 to the rim of the envelope in the usual manner. Four rigid metal pins 15, 16, 17 and 18 (see FIG. 2) are hermetically sealed through the wafer 14 and spaced equal distances from each other around the circumference of the wafer. A concentrated light source such as a planar tungsten filament 20 having a plurality of interconnected coil sections arranged in monoplane or biplane relationship is suspended within the envelope 12 by a mount assembly consisting of a pair of support wires 22, 24 that are held in spaced-apart relation by a pair of non-conductive bridges 26 and 28. The supports 22, 24 are terminated by helical-coiled segments 23 and 25, respectively, that are slipped over and fastened as by spot welding to oppositely disposed pins 15 and 17, as shown. The planar filament 20 is electrically connected to the support wires 22, 24 by short end coils 21 that are spot welded in telescoped relation with slip coils force-fitted over the support wires. Hooked filament-support wires 27 and 29 are anchored in the top and bottom bridges 26 and 28, respectively, and coupled to the uncoiled segments of the filament 20 that join the coil sections. A detailed description of the mount assembly and the manner in which it is fabricated is disclosed in the aforementioned copending application of N. J. Rainone et al. Ser. No. 100,665.

Since the wire supports 22, 24 are fastened to pins 15 and 17, the latter are connected to the filament 20 and thus constitute a pair of rigid oppositely-disposed main conductors. The remaining pins 16 and 18 thus serve as a pair of rigid auxiliary conductor members.

The envelope 12 and wafer 14 are composed of quartz or a suitable high-silica content glass (such as "Pyrex" borosilicate glass No. 7740 marketed by the Corning Glass Works) and the envelope contains a mixture of a halogen and an inert fill gas — a mixture of bromine and nitrogen at a pressure of about 1,000 torrs for example. The bridge members 26 and 28 are composed of quartz and all of the metal parts of the mount assembly enclosed within the envelope 12 are composed of tungsten.

A suitable base member such as a metal shell 30 having a keyed post 31 is fastened to the neck of the envelope 12 by a suitable cement 32 in the usual manner.

In accordance with the present invention, a fuse 34 consisting of either a platinum-plated nickel wire or a platinum-plated Nichrome alloy wire is attached to one of the auxiliary conductors and an adjacent main conductor (pins 16 and 17 in the lamp 10 illustrated in the drawing). The fuse wire 34 is fastened, as by spot welding, to the inner ends of the pins 16, 17 at locations adjacent to but spaced from the envelope end wall 14. The fuse 34 is thus connected in series with the filament 20 by pins 16 and 17 which it bridges. The outer ends of pins 15 and 16 accordingly constitute exposed longitudinally-extending terminals for the lamp 10.

A protective sleeve such as a loose-fitting glass tube 36 is desirably placed over the fuse wire 34 to guard against the possibility that molten metal from the activated fuse will strike the envelope walls and cause them to crack when the lamp fails. As will be noted in FIG. 2, the glass tube 36 is locked in such position by the connected segments of pins 16, 17.

In the case of the 500 watt T10 projection lamp 10 illustrated having a biplane filament 20 designed to operate at a voltage within a range of from 110 to 130 volts, satisfactory results have been obtained by spacing the pins 16 and 17 approximately 11 millimeters apart and using a platinized Nichrome wire 16 millimeters long and approximately 0.4 millimeters in diameter as the fuse 34. The platinum coating or sheath was of such thickness that it protected the Nichrome core from the halogen gas without interfering with the fusing action. Excellent results have been obtained by employing Nichrome wire having a platinum sheath such that the platinum comprises approximately 62 percent by weight of the wire. The thickness of the platinum coating can vary and Nichrome wires wherein the platinum comprises from about 30 to 70 percent by weight of the wire can be used.

"Nichrome" is the trade name for a series of nickel-based alloys (made by the Driver-Harris Company) which melt at approximately 1,350°C. and contain from 11 to 22 percent chromium, smaller amounts of silicon or manganese, and optionally some iron. Such alloys are well known in the art and are used extensively as electric-resistance heating elements. A specific example of a suitable Nichrome alloy is one which contains 75 percent nickel, 12 percent iron, 11 percent chromium and 2 percent manganese.

Since nickel has only a slightly higher melting point (1,450°C) than Nichrome alloy, the same fusing action can also be obtained by using a platinum-coated nickel wire of the same dimensions in place of the above-described platinized Nichrome wire fuse element.

While the fuse 34 as illustrated in the drawing and described is a platinum-clad wire of substantially

uniform diameter, a composite multi-section wire which has a medial segment of reduced thickness that is composed of platinized nickel or a platinized Nichrome alloy and serves as the fusible member can also be employed. In any event, the opening in the electrical circuit formed when the fuse melts is greater than the maximum arcing distance for the operating voltage of the filament — that is, the gap produced within the lamp envelope by the melted fuse wire when the filament fails is too large to support an arc in the halogen-containing atmosphere of the lamp.

I claim as my invention:

1. In a regenerative-type incandescent lamp having a sealed light-transmitting envelope that encloses a coiled tungsten filament and a halogen-containing atmosphere, the improvement comprising a fuse component that is connected in series with said filament, is located within said envelope, and is composed of a material selected from the group consisting of platinized nickel and a platinized nickel-chromium alloy that contains less than 11 percent silicon or manganese.

2. The improvement of claim 1 wherein; said filament is connected to a pair of elongated rigid main conductors that are embedded in an end wall of said envelope, a rigid auxiliary conductor is anchored in said envelope end wall and spaced from each of said main conductors, said fuse component is connected to said auxiliary conductor and one of said main conductors, said auxiliary conductor and said one main conductor extend through the end wall of the envelope and thereby constitute a pair of exposed terminals for the lamp, and the interior portions of said main and auxiliary conductors are composed of tungsten.

3. The improvement set forth in claim 1 wherein platinum comprises from about 30 to 70 percent by weight of the fuse component.

4. The improvement set forth in claim 2 wherein; said lamp comprises a single-ended projection lamp, said tungsten filament comprises a planar array of interconnected coil sections, said main and auxiliary conductors each comprise a tungsten pin, and said fuse component comprises a wire of predetermined and substantially uniform diameter.

5. The projection lamp of claim 4 wherein; said envelope is composed of borosilicate glass and contains a mixture of an inert gas and bromine, and each of said tungsten pins extend through the end all of said envelope.

6. The projection lamp of claim 4 wherein; said envelope is of tubular configuration and contains a mixture of nitrogen and bromine, said fuse component comprises a platinum-plated wire of said nickel-chromium alloy wherein platinum constitutes approximately 62 percent by weight of the wire, and a loose-fitting glass tube is disposed in sleeved-protective relationship with the fuse wire and is retained in such position by the connected portions of the associated pins.
